UNITED STATES PATENT OFFICE.

NATHANIEL W. FENTON, OF EAST CAMBRIDGE, MASSACHUSETTS.

BEVERAGE VAN OR WAGON.

SPECIFICATION forming part of Letters Patent No. 268,475, dated December 5, 1882.

Application filed August 14, 1882. (No model.)

To all whom it may concern:

Be it known that I, NATHANIEL W. FENTON, of East Cambridge, in the county of Middlesex, of the State of Massachusetts, have invented a new and useful Improvement in Beverage Vans or Wagons; and I do hereby declare the same to be described in the following specification and represented in the accompanying drawings, of which—

10. Figure 1 is a vertical and longitudinal section, and Fig. 2 a horizontal section, of a wagon of my invention. It is designed to be moved about from place to place for retailing beer, soda-water, or other beverage to individuals.

15. The nature of the said invention is defined in the claims hereinafter set forth.

In the drawings, A represents a wagon having constructed within and constituting an integral part of it a refrigerator or ice-holding 20 apartment, B, there being suitably arranged within such apartment a closed fountain or reservoir, C. From the top of the refrigerator, and over the fountain, there extends upward a hollow prismatic column, E, having 25 one or more openings, a, and a door or doors b to such in one or more sides of it, such column serving to support the educts or discharging pipes or conduits e f of the fountain C, such conduits being arranged as represented 30 and provided with cocks g g. On the top of the column E is arranged or fixed a vessel, F, for holding syrup, such vessel having one or more faucets or cocks, h, for drawing off its liquid contents, as may be necessary. Within the 35 refrigerator there also is a tank, D, for holding beer, such tank having a discharge-pipe, i, arranged and terminating in a faucet or cock, k, as represented. There is also to the refrigerator a shelf or tablet, l, for supporting tumblers or other vessels, such shelf or tablet being arranged as represented. The educt e' of 40 the fountain C extends down within the fountain from the top nearly to the bottom thereof; and for the purpose of cleansing the fountain 45 or charging it with a liquid—as soda-water, or water impregnated with carbonic-acid gas, or with air alone, as may be required—there is led out of its bottom and through that of the wagon-body a pipe, m, furnished with a cock, 50 n, such pipe having at its lower end a coupling-screw, o. There is to the wagon-body a top, p, supported by suitable standards, q, and there is above each permanent or fixed side of the body, and depending from the roof, one or 55 more "roll-up" curtains, r. The driver's seat

is shown at s as having a chamber or box, t, beneath it and front of the refrigerator. The said refrigerator is arranged at one side of the body of the wagon, so that there may be a clear working-space, u, between the refrigerator and the opposite side and in rear of the said refrigerator, in order that an attendant may pass freely about one side and end of the refrigerator, as occasion may require, it being understood that in such side there is to be one or more openings provided with a door or doors, v, in order for access to be had to the interior of the refrigerator to supply it with ice or for other purpose.

A "beverage van" or wagon thus constructed can be drawn from place to place and employed to advantage in furnishing cooling-drinks to persons in the streets of a city or town or at fairs or other public places.

I am aware that a wagon has been devised for conveying mineral-water retorts, and also that a hand-cart has been invented for carrying about a soda-water fountain and its accessories. I regard my device as a decided improvement upon the latter construction. My device is arranged for conveying other articles than soda-water, as beer, and also for convenience in getting at the various portions. An attendant can enter the wagon, where there is shelter—in fact, the complete device forms a portable shop, containing within itself all the necessary conveniences for business.

Having described my invention, what I claim is—

1. A wagon such as described, in combination with a contained refrigerator and soda-water apparatus, the latter occupying only a portion of the interior of the wagon, whereby there is room for an attendant within, as set forth.

2. The wagon A, in combination with the refrigerator B, formed integral therewith, the reservoir C, seated within the refrigerator, its pipes e' e f, the column E, and syrup-vessel F, constructed and arranged as set forth.

3. The wagon A and refrigerator B, formed integral therewith, in combination with the reservoir C, its pipes e' e f, column E, syrup-vessel F, beer-tank D, and its pipe i, all constructed and arranged as set forth.

NATHANIEL W. FENTON.
